DESIGN FOR A COMBINED CIGARETTE CASE AND LIGHTER

Archie M. Andrews, Greenwich, Conn., assignor to Platinum Products Corp., New York, N. Y., a corporation of New Jersey

Application March 10, 1938, Serial No. 75,721

Term of patent 7 years

To all whom it may concern:

Be it known that I, Archie M. Andrews, a citizen of the United States, residing at Greenwich, in the county of Fairfield and State of Connecticut, have invented a new, original, and ornamental Design for Combined Cigarette Case and Lighter, of which the following is a specification, reference being made to the accompanying drawing, forming a part thereof.

open position.

I claim:

The ornamental design for a combined cigarette case and lighter as shown.

ARCHIE M. ANDREWS.
